UNITED STATES PATENT OFFICE.

THOMAS H. BOWDIDGE, OF BOSTON, MASSACHUSETTS.

TACK-HAMMER.

1,097,521.

Specification of Letters Patent. Patented May 19, 1914.

Application filed February 26, 1913. Serial No. 750,791.

To all whom it may concern:

Be it known that I, THOMAS H. BOWDIDGE, a citizen of the United States, residing at 39 Haverhill street, in the city of Boston, county of Suffolk, and State of Massachusetts, have invented a new and useful Improvement in Tack-Hammers, of which the following is a specification.

The present invention relates to tack hammers and more particularly to that class of tack hammers provided with tack magazines.

It has been customary heretofore to provide the tack hammer with a hollow handle which thus serves as a tack magazine. This construction requires a readily removable closure of some kind to close the open end of the handle to hold the tacks therein. Tack hammers having tack magazines located in their handles have a limited capacity for tacks and are difficult to operate, when it is desired to remove tacks, owing to the necessity of removing the closure.

The object of the present invention is the provision of a light and cheap tack hammer provided with a magazine of simplified and improved construction which is convenient to operate, which will hold a larger quantity of tacks than that which has heretofore been practicable and which with less expenditure of time and effort will permit the removal of tacks therefrom.

To the accomplishment of this object and such others as may hereinafter appear the features of the invention relate to certain devices, combinations and arrangements of parts, hereinafter described and then set forth in detail in the appended claims, which possess advantages readily apparent to those skilled in the art.

The various features of the present invention will be best understood from an inspection of the accompanying drawing illustrating the best form of the invention at present known to the inventor, in which,

Figure 1 is an elevation of the tack hammer, and Fig. 2 is an underside plan on the line 2—2, Fig. 1.

In the illustrated embodiment of the invention the tack hammer consists of a hammer head 1, a handle 2, and an independent tack magazine 3. The hammer head 1 is pro-

vided with a central bore 4 which is internally threaded to receive a threaded rod 5 projecting from the tack magazine 3. The tack magazine is provided at its lower end 55 with a central bore 6 which is internally threaded to receive a threaded rod 7 having a head 8 which is pinned to the upper end of the handle 3. With this construction the tack magazine may be detached and the hammer head 1 directly connected to the handle 3 by rotation of the head on the threaded rod 7.

The tack magazine 3 consists of an exterior fixed cylindrical casing 9 and an interior rotatable cylindrical casing 10 arranged concentrically of the casing 9. The casings are provided respectively with openings 11 and 12. By rotating the casing 10 within the casing 9 the openings 11 and 12 65 may be caused to register to permit the introduction of tacks into and their removal from the casing 10. To provide means for such rotation the casing 10 carries a knob 13 which may be grasped by the operative 70 when it is desired to rotate the casing 10. The knob also acts as a stop to limit the extent of rotation of the casing 10.

In use the knob 13 is grasped and the casing 10 rotated to the right (Fig. 1) to cause 80 the openings 11 and 12 to register. A quantity of tacks is then introduced into the magazine and the opening closed by a reverse rotation of the casing into the position of Fig. 1. When it is desired to obtain tacks from 85 the magazine the handle is grasped by the right hand, the casing 10 is rotated to the right, Fig. 1, and the tacks are dumped out to the extent required into the palm of the left hand by a twist of the wrist of the right 90 hand.

What is claimed as new, is:

1. The combination with a hammer head having an internally threaded socket, of a handle having an externally threaded stud 95 to fit the socket in the head, whereby said handle may be detachably connected to the head, and a tack magazine having an externally threaded stud at one end adapted to fit the socket in the hammer head, said magazine also having an internally threaded socket at its other end to fit the stud on the 100

handle, whereby said magazine may be detachably mounted between the head and handle.

2. The combination with a hammer head and handle having means for detachably connecting them to one another, of a tack magazine having means at its opposite ends

for detachably connecting it to and between the head and handle.

THOMAS H. BOWDIDGE.
